VANITY CASE

Filed Feb. 9, 1926

Patented Sept. 18, 1928.

1,684,454

UNITED STATES PATENT OFFICE.

HARRY W. NOYES, OF WEST HAVEN, CONNECTICUT, ASSIGNOR OF ONE-HALF TO
A. GRAHAM SHIELDS, OF NEW HAVEN, CONNECTICUT.

VANITY CASE.

Application filed February 9, 1926. Serial No. 87,144.

This invention relates to a new and improved vanity case particularly of the loose powder type.

It is the object of this invention, among other things, to provide a vanity case, wherein the powder may be contained in loose form without possibility of leakage, but may be readily ejected therefrom onto the hand, a compress, or the like, the supply of powder easily replenished, so designed that the cover cannot be closed if the parts are arranged for the discharge of powder or powder discharged if the cover is closed, to improve the detail construction of the case, and in other ways produce a more simple and efficient vanity case than any heretofore made.

To these, and other ends, my invention consists in the vanity case, as will be hereinafter described and more particularly pointed out in the claims,

In the drawings, wherein like numerals of reference designate like parts in the several figures;

25 Figure 1 is a front elevation of my improved vanity case;

Figure 2 is a plan view of the body member, the cover being removed and the top of the powder compartment broken away;

30 Figure 3 is an enlarged fragmentary view of some of the parts in horizontal section, as indicated on the plane of the line 3—3 of Figure 4;

Figure 4 is an enlarged front elevation of the body member and some of the adjacent parts, a portion of the body being broken away to show the interior mechanism;

40 Figure 5 is an enlarged detail section of some of the parts on the line 5—5 of Figure 4;

Figure 6 is a front elevation of a modified form of the invention.

45 Figure 7 is a sectional elevation of a portion thereof on the line 7—7 of Figure 6, but with the slide shown in another position and the powder ports in register with each other; and

50 Figure 8 is an enlarged fragmentary view thereof in horizontal section, as indicated on the plane of the line 8—8 of Figure 6.

In the embodiment of the invention herein shown, 10 designates the body, which is circular in form, having a bottom portion

11 and side walls 12, which terminate at 55 their upper ends in a neck portion 16; 13 the cover, which is preferably hinged to the body and having a top portion 14 and side walls 15, the lower ends of which encircle the neck portion 16 of the body at 48 when 60 the cover is in closed position.

While I have illustrated the vanity case as being circular in form, obviously it may be made in other desired forms.

Through the walls 12 are a plurality of 65 powder ports 17, shown herein as two in number and adjacent thereto is a slot 18 and two leak ports 19.

Within the body and encircling the inside of the walls 12 is a band 20, which is 70 held in place by its frictional engagement therewith and to provide a space 21 therebetween for a limited distance. The opposite ends of this band overlap, substantially as shown in Figure 3. Through this band 75 are a plurality of powder ports 22 which are in register with the powder ports 17.

Movably mounted in the recess 23 in the outer wall of this band is a slide 24, having a plurality of powder ports 25, which are 80 spaced apart a distance, the same as that of the powder ports 17 and 22, and preferably integral therewith and projecting outwardly therefrom through the slot 18 is a finger tab 26.

Resting on the top of this band 20 and held therein by an engagement of the periphery thereof with the inner wall of the body is a disk 27, through the center of which is an opening surrounded by a collar 90 29, which contains a flexible diaphragm 28. The space between the bottom 11 and the disk 27 and diaphragm 28 is the powder compartment and in use is filled with powder, the usual compress being positioned 95 under the cover, resting generally upon the top of the disk 27. The diaphragm 28 is flexible and when pressed downwardly into the powder compartment, powder 46 is ejected therefrom through the powder ports 100 when in register with each other. A new supply of powder is placed in the powder compartment through the opening in the disk 27 after removal of the diaphragm 28, an operation requiring little labor.

The cover is held in its closed position by the spring catch 30, connected with a lock spring 47 fixed to the wall 12, and moves

within the space 21, being manipulated from the exterior through the finger piece 31 connected therewith.

In the lower edge of the cover wall 15 is a notch 32 which registers with the upper end of the finger tab 36 when the slide is in the position substantially as shown in Figure 3, at which time the powder ports 17 are closed. This cover will not close if the notch 32 is not in the position indicated, because the notch 32 will not register with the finger tab 26. This will indicate that the powder ports 17 are not closed.

When the slide 24 is moved in the recess to the right, as shown in Figure 3, and this can only be done when the cover is open, because it is necessary to release the finger tab from the notch 32, the powder ports 22, 25 and 17 are brought into register with each other, at which time powder from the powder compartment may be ejected therethrough by pressure upon the diaphragm 28. After a sufficient quantity of powder has been obtained, the slide is returned to its former position, thus shutting off the supply of powder and moving the parts so that the cover can be again closed. If any powder should leak through from the powder compartment, between the slide and its adjacent walls, which, of course will only be a very limited quantity, it will escape through the leak ports 19. Thus, there will be no clogging of the slide, which might occur if powder accumulated in the ends of the recess 23 without an opportunity to escape therefrom.

In Figures 6, 7 and 8, I have illustrated a modified form of my invention, wherein the powder compartment is within the inverted cup 33, formed with a head portion, having a flexible diaphragm 36 in the central opening thereof and side walls 35. The powder ports 37 in the wall 35 are in register with similar powder ports 38 in the outwardly projecting band portion 39 on the wall of the body. Inside this band portion and between the wall 35, is a slide 40, having powder ports 41 therethrough, which are moved into and out of register with the powder port 38. At the ends of the band portion 39 are leak ports 42 for the escape of any powder that may accumulate in the slide or recess.

Integral with the cover 13 of this form of case is a lug 43 that projects downwardly over the band portion 39, and in front of the finger tab 44, when the powder ports are not in register with each other, substantially as shown in Figure 8. When thus positioned, it is impossible to manipulate the slide 40 until the cover is opened. Unless the tab 44 is in the position wherein the ports are closed, it will be also impossible to close the cover, because the lower end of the lug 43 will strike the top of the tab 44.

A catch or clasp 45 of any usual form is provided to lock the cover against accidental opening.

Within the scope of the appended claims, minor changes and alterations may be made, aside from those herein suggested, and I would therefore have it understood, that I do not limit myself to the exact construction herein shown and described. 70

Having described my invention, what I claim as new and desire to secure by Letters Patent, is:

1. In a vanity case; a body member; a powder compartment therein; powder ports through the walls thereof from the interior of the powder compartment to the exterior of the case; and a flexible diaphragm within the body member forming one wall of the powder compartment and a closure member for covering the ports. 80 85

2. In a vanity case; a body member; a powder compartment therein; powder ports through the walls thereof from the interior of the powder compartment to the exterior of the case; and a flexible diaphragm within the body member forming an interior wall of the powder compartment and a closure member for covering the ports. 90

3. In a vanity case; a cover; a body member having a powder compartment therein; powder ports through the walls thereof; and means for covering and uncovering the powder ports movable in a path below the top of the body, said means having associated therewith a member which will hold the cover against closing until the powder ports are covered against the passage of powder therethrough. 95 100

4. In a vanity case; a body member having discharge ports through the side walls thereof; means for covering and uncovering said ports movable in a path below the top of the body; a cover connected with the body member; and means connected with the cover for preventing the opening of the ports while the cover member is in its closed position. 105 110

5. In a vanity case; a body member having a powder compartment therein; powder ports through the side walls thereof; a slide movable in a path substantially parallel with said side wall, that is manipulated from the exterior of the body member, for covering and uncovering said powder ports and having a finger tab or the like connected therewith; and a cover member having a part thereon that projects into the path of movement of the finger tab and prevents movement of the slide while the cover is in its closed position. 115 120 125

6. In a vanity case; a body member having a powder compartment therein; powder ports through the side walls thereof; a slide movable in a path substantially parallel with said side wall, that is manipulated from the 130

exterior of the body member, for covering and uncovering said powder ports and having a finger tab or the like connected therewith; and a cover member having a part thereon that projects into the path of movement of the finger tab and prevents movement of the slide while the cover is in its closed position, the relative position of the tab being such that when the ports are uncovered the tab is in the path of movement of a part connected with the cover and thereby prevents the closing thereof.

7. In a vanity case; a body member having powder ports through the side walls thereof and a powder compartment therein; a member within the powder compartment having ports therethrough which register with the ports in the body member; and a slide operative between the body member and said other member and having ports therethrough which in one of its positions register with the aforesaid ports.

8. In a vanity case; a body member having powder ports and leak ports through the side walls thereof and a powder compartment therein; a slide having ports therethrough, which in one position register with the ports in the body member, operative adjacent to the inside of the wall of the body member and so arranged that a leak port is opposite the limit of movement thereof in each direction.

9. In a vanity case; a body member having a slot and powder ports through the side walls thereof and a powder compartment therein; a slide movably mounted inside the wall of the body member, having ports therethrough which in one of its positions register with the powder ports and having a finger tab thereon that projects through said slot; and a cover movably connected with the body member and so formed that by reason of said tab said cover cannot be moved into its closed position when the ports in the slide and body member register with each other.

10. In a vanity case; a body member having a slot and powder ports through the side walls thereof and a powder compartment therein; a slide movably mounted inside the wall of the body member, having ports therethrough which in one of its positions register with the powder ports and having a finger tab thereon that projects through said slot; and a cover movably connected with the body member and so formed that by reason of said tab said cover cannot be moved into its closed position when the ports in the slide and body member register with each other and the slide cannot be moved when the cover is in its closed position.

11. In a vanity case; a body member having powder ports through the side walls thereof and a powder compartment therein; a member within the powder compartment having a peripheral recess in one wall there-

of and powder ports therethrough adjacent to said recess; a slide below the top of the body member and movable in a peripheral path within said recess and having ports therethrough, which in one of its positions register with all said powder ports and thereby provide a discharge opening for the powder within the powder compartment.

12. In a vanity case; a body member having a powder compartment therein and from which powder is discharged therefrom through the side wall of the body member; and a flexible member within the body member of less diameter than the body member and surrounded by a rigid wall, which when pressed will eject the powder from the powder compartment through an opening in said side wall.

13. In a vanity case; a body member having powder ports through the side walls thereof and a powder compartment therein; a band within the powder compartment having ports therethrough which register with the ports in the body member; a disk within the body member and resting upon the band and having an opening therethrough; and a flexible diaphragm within said opening forming a removable closure member for the powder compartment.

14. In a vanity case; a body member having powder and leak ports through the side walls thereof and a powder compartment therein; a member within the powder compartment having a recess in one wall thereof and powder ports therethrough adjacent to said recess; a slide movably mounted in said recess and having ports therethrough, which in one of its positions register with all said powder ports and thereby provide a discharge opening for the powder within the powder compartment, the said leak ports being arranged in the side walls of the body member substantially opposite the ends of said recess.

15. In a vanity case; a body member having a powder port through one of the walls thereof; an inverted cup within the body member having powder ports therethrough; a flexible diaphragm within the head portion of the inverted cup; and a cover movably connected with the body member.

16. In a vanity case; a body member having a powder port through one of the walls thereof and a neck portion of reduced diameter at one end; an inverted cup within the body member having powder ports therethrough and retained within the body member in part by said neck portion; a flexible diaphragm within the head portion of the inverted cup; and a cover movably connected with the body member.

17. In a vanity case; a body member having a powder port through one of the walls thereof; an inverted cup within the body member having powder ports therethrough;

an opening through the head portion thereof; a flexible diaphragm in the opening; and a cover movably connected with the body member.

5 18. In a vanity case; a body member having a powder port through one of the walls thereof; an inverted cup within the body member having powder ports therethrough; a flexible diaphragm within the head portion of the inverted cup; a cover movably connected with the body member; and a slide between the side walls of the body and cup, to cover and uncover the ports.

10 19. In a vanity case; a body member having a laterally projecting band portion upon one side thereof with powder ports therethrough and leak ports through the side walls thereof; an inverted cup within the body member having powder ports therethrough; a flexible diaphragm connected with the inverted cup; and a slide movably mounted between the walls of the band portion and the inverted cup, to cover and uncover the ports.

15 20. In a vanity case; a body member having a powder port through one of the walls thereof; an inverted cup within the body member having powder ports therethrough and a head portion; a flexible diaphragm, cup shape in cross section having an overhanging flange at one end thereof that projects over said head portion; and a cover movably connected with the body member.

25 21. In a vanity case; a body member having powder ports through one of the walls thereof; an inverted cup within the body member having powder ports through one of the walls thereof; an opening through the head portion thereof; a flexible diaphragm in the opening and held against endwise movement therein in one direction; and a cover movably connected with the body member.

35 22. In a vanity case; a body member having powder ports through one of the walls thereof; an inverted cup within the body member having powder ports through one of the walls thereof; an opening through the head portion thereof, and a downwardly projecting flange therearound; a flexible diaphragm in the opening and held against endwise movement therein in one direction; and a cover movably connected with the body member.

45 23. In a vanity case; a body member having a powder port through one of the walls thereof; an inverted cup within the body member having powder ports therethrough; an opening through the head portion thereof; a flexible diaphragm in the opening, positioned in a plane different than that of the ports, the relation between said body member and cup being such as to form a

55 powder compartment therebetween having rigid walls all around the same except at one side which is partially flexible.

24. In a vanity case; a body member having a powder port through one of the walls thereof and a rigid, unyielding bottom; an inverted cover within the body member having powder ports therethrough, said cup having a head portion of unyielding material substantially parallel with the bottom of the body member; and a flexible diaphragm of less diameter than that of the inverted cup within the head portion of the cup.

70 25. In a vanity case; a body member having a powder port through one of the walls thereof; an inverted cup within the body member having powder ports therethrough and a head portion forming a part thereof; a flexible diaphragm; and means for connecting said flexible diaphragm to said head portion, whereby the same is positioned between the said head portion and bottom of the body member.

75 26. In a vanity case, a cup shaped body having a discharge opening in its rim, a top for the body having a depending flange fitted in the rim and provided with an opening in register with the opening of the rim, a slide mounted between the rim and flange and having ends disposed beneath the top and having an opening for registry with the rim and flange openings and means to actuate the slide.

80 27. In a vanity case, a body having a side wall formed with a discharge opening, a slide having an opening for registry with the discharge opening, a member on the interior of the body, said slide being disposed between the wall and member and one of the latter being formed with a cut-out in which the slide is received, means to operate 105 the slide, and means to restrict sliding movement of the slide.

85 28. In a vanity case, a body having a side wall formed with a discharge opening, a slide having an opening for registry with the discharge opening, a member on the interior of the body, said slide being disposed between the wall and member, means to operate the slide, and means to restrict sliding 110 movement of the slide.

90 29. In a vanity case; a body having discharge ports through its side walls; a cover for the body member; means for covering and uncovering said ports movable in a path below the top of the body and having a part 115 thereon, which part will prevent positioning of the cover on the body in its closed position if said discharge ports are uncovered.

95 In testimony whereof, I have hereunto affixed my signature.

HARRY W. NOYES,
